UNITED STATES PATENT OFFICE.

RICHARD I. RATNER, OF NEW YORK, N. Y., ASSIGNOR TO THE LIBBEY GLASS MANUFACTURING COMPANY, OF TOLEDO, OHIO, A CORPORATION OF OHIO.

DESIGN FOR A GOBLET.

Application filed November 24, 1926. Serial No. 19,834. Term of patent 7 years.

To all whom it may concern:

Be it known that I, RICHARD I. RATNER, a citizen of the United States, residing at New York, in the county of New York and State of New York, have invented a Goblet, of which the following is a specification, reference being had to the accom-

panying drawing, forming a part thereof. The figure is a side elevation of a goblet, showing my new design.

I claim:

The ornamental design for a goblet, as shown.

RICHARD I. RATNER.
